DESIGN FOR A WAITER'S TRAY

John Le Graffe, Beverly Hills, Calif.

Application September 17, 1945, Serial No. 122,119

Term of patent 14 years

(Cl. D44—19)

To all whom it may concern:

Be it known that I, John Le Graffe, a citizen of the United States, residing in Beverly Hills, county of Los Angeles, State of California, have invented a new, original, and ornamental Design for a Waiter's Tray, for which the following is a specification, reference being had to the accompanying drawing, forming a part thereof.

I claim:

The ornamental design for a waiter's tray, as shown.

JOHN LE GRAFFE.
